UNITED STATES PATENT OFFICE.

FRANK W. ANDREWS, OF WAPAKONETA, OHIO, ASSIGNOR, BY MESNE ASSIGNMENTS, TO THE SUPERIOR REFRIGERATING COMPANY, OF WAPAKONETA, OHIO, A CORPORATION OF OHIO.

THERMOELECTRIC APPARATUS.

Application filed May 14, 1917. Serial No. 168,526.

To all whom it may concern:

Be it known that I, FRANK W. ANDREWS, citizen of the United States, residing at Wapakoneta, in the county of Auglaize and State of Ohio, have invented certain new and useful Improvements in Thermoelectric Apparatus, of which the following is a specification.

My invention relates to a thermo electric apparatus in which a reduction of temperature is effected electrically by means of a thermo electric battery or thermopile involving the theory or principle commonly known as Peltier's effect.

16 The object of the invention is to provide improved form of electrical insulation for the thermo electric couples or pairs which will obviate short circuiting without affecting the variation of temperature induced 20 by the apparatus.

With the above primary and other incidental objects in view as will more fully appear in the specification, the invention consists of the features of construction, the 25 parts and combinations thereof, and the mode of operation or their equivalents, as hereinafter described and set forth in the claims.

Referring to the drawings—

30 Fig. 1 is a perspective view of the thermo electric battery or thermopile, as adapted for embodiment in refrigerating apparatus. Fig. 2 is a side elevation partly in section illustrating the contact or juncture of the 35 members comprising the thermo electric couples or pairs. Fig. 3 is an end elevation thereof. Figs. 4 and 5 are detail views illustrating the form of joint or juncture between the individual members of each 40 thermo electric couple.

Like parts are indicated by similar characters of reference throughout the several views.

The present invention is dependent to 45 some extent upon the principle or condition of electrical science pertaining to the heating or cooling of the juncture or contact point of two or more dissimilar metals connected in a circuit, or of different parts of one 50 metal which are in dissimilar physical states to induce an electrical current between the extremities of such metallic members or bodies, or dissimilar parts thereof which is 55 the recognized theory of thermo electricity and particularly upon the converse of this

rule or principle, viz, that the rise or fall of temperature at the juncture of two dissimilar metals or two portions of the same metal in dissimilar physical state is effected by the passage of an electric current from 60 one metal or portion to the other across the juncture. This thermal effect is distinct from the rise of temperature due to the electrical resistance of the metal, and changes sign when the direction of the current across 65 the juncture is changed. This is what is known as Peltier's phenomenon.

While Peltier's phenomenon has been more or less generally known heretofore, no practical method has been devised for applying 70 this theory or principle to practical purposes.

Referring to the drawings, 1 is a refrigerator of the usual type of which 2 is the refrigerating compartment commonly known 75 as the "ice" compartment, and 3 is the commodity or chill compartment. The thermo electric battery or thermopile hereinafter described is preferably located in the refrigerating or "ice" compartment 2. In the 80 commodity or chill compartment there is located a thermostat 4 adapted to open and close certain electrical contacts whereby the operation of the thermopile is controlled.

In constructing the thermal electric battery or thermopile various metals of dissimilar physical properties may be employed. In practice, contacted bars of antimony and bismuth have been found most efficient, however, other materials of the 90 thermo electric series such as lead, zinc, copper or iron may be employed. These materials may be in the form of solid bars or may be granular or in the form of chips or filings.

In the drawings there have been shown two series of thermo-electric members arranged in transverse relation in a stack or pile "cob house" fashion. Each one of the thermo electric members is enclosed in an insulating tube or closure of heat conductive material preferably glass. The series of electrical insulating containers or glass tubes a^1 , a^2 , a^3 , a^4 , a^5 , a^6 and a^7 and a^8 each contain a body or core of antimony. The 105 transverse electrical insulating enclosures or glass tubes b^1 , b^2 , b^3 , b^4 , b^5 , b^6 , b^7 and b^8 each contain a body or core of bismuth. The enclosures or tubes 5 of both series are closed at their ends by rubber stoppers 6, 110

which not only electrically protect and insulate the enclosed metallic bodies, but also tend to compensate for the expansion thereof due to varying degrees of temperature.

In the drawing the bismuth and antimony members have each been separated into two subdivisions or series electrically connected in multiple in the energizing circuit.

One terminal of the circuit is connected 10 through the terminal stopper or insulating plug 6 of the enclosure or container a^1 , with the enclosure core or body of antimony while a branch line connects with the enclosed body of antimony in the enclosure 15 or container a^2 through the terminal stopper 6 thereof. Likewise the opposite side of the circuit is connected through the terminal stoppers 6 with the enclosed bodies 20 or cores of bismuth in the enclosing tubes or containers b^1 and b^2 . In order that the enclosed bodies or cores may make electrical contact one with the other, the insulating enclosures or tubes 5 are notched or recessed 25 as shown in Figs. 4 and 5. The enclosure or tube of one member of thermal electric pair is provided with oppositely disposed arcuate notches 7 the radius of which is substantially equal to that of the transversely disposed tube or container to be engaged. 30 These notches 7 are of sufficient depth to expose the enclosed metallic bodies as at 8. The opposing insulating container or enclosure illustrated in Fig. 5 is also provided with oppositely disposed arcuate notches 9 35 of smaller size, the radius of which is substantially equal to that of the enclosed metallic body exposed at 8 in Fig. 4. These notches 9 intersect the enclosed metallic body of the second insulating enclosure or 40 tube. When these members are interlocked one with the other, the exposed portion 8 of the enclosed metallic body of the first member engages within the arcuate notches 9 of the second member, and within the notch 45 or slight depression in the enclosed metallic body of the second member, with which it makes electrical contact. At the same time the exterior periphery of the insulating enclosure or tube of the second member engages 50 within the arcuate notches 7 of the first member to make a perfect insulating joint therewith. The enclosed metallic bodies may be electrically united in any suitable manner, and if the thermopile is to 55 be submerged in a brine tank or employed in other association where moisture might enter the joints of the insulating containers 5, such containers may be united or hermetically sealed. By arranging the 60 thermo-electric members transversely in double series as shown in Fig. 1, four separate series of juncture points are provided. Under the established rule of thermal electricity, the electro motive force or effect of 65 the succession of junctures of the multipli-

cation of the thermal electric couples or pairs is the sum of the separate forces or effect for the successive junctures. Therefore the capacity of the apparatus for refrigerating purpose may be increased or 70 diminished in proportion to the number of thermo-electric members and the number of juncture points provided.

From the above description it will be apparent that there is thus provided a device 75 of the character described possessing the particular features of advantage before enumerated as desirable but which obviously is susceptible of modification in its form, proportion, detail construction or arrangement of parts, without departing from the principle involved or sacrificing any of its advantages.

While in order to comply with the statute the invention has been described in language 85 more or less specific as to certain structural features, it is to be understood that the invention is not limited to any specific details but that the means and construction herein described comprise but one mode of 90 putting the invention into effect and the invention is therefore claimed broadly in any of its possible forms or modifications within the scope of the appended claims.

Having thus described my invention, I 95 claim:

1. In a construction of the character described, a pair of thermo electric elements, arranged transversely in relation one with the other, a tubular enclosure for each element, said enclosures being notched at the point of intersection to expose the element in one enclosure to contact with the element in the other enclosure, the juncture of the 100 closures being sealed.

2. In a construction of the character described, cylindrical thermo electric elements, cylindrical tubular enclosures therefor, one element and enclosure therefor having therein an arcuate notch having a radius substantially equivalent to that of the other cylindrical electro thermal element, the other element enclosure having therein an arcuate notch, the radius of which substantially agrees with that of the first enclosure, the 110 element within the second enclosure being unnotched, the notched portions of said enclosures being interengaged angularly one with the other with the elements making 115 contact through said notches.

3. In a construction of the character described, electro thermal elements angularly arranged in a criss cross stock and intercommunicating enclosures therefor within 120 which the elements make contact one with the other.

4. In a construction of the character described, a plurality of intersecting tubular enclosures angularly arranged in relation one 125 with another, and contacting thermo electric

- elements enclosed within said tubular enclosures.
5. In a construction of the character described, a plurality of angularly arranged thermo electric elements, tubular enclosures therefor, the enclosed elements separated into a plurality of series and stacked with enclosed elements of different series, alternating with each other in substantially cob house fashion, said tubular enclosures having registering openings therein through which the thermo electric elements make contact one with another.
6. In a construction of the character described, a pair of thermo electric members, tubular enclosures therefor, said enclosures being notched and arranged with the notches of the respective enclosures in registry one with the other, said elements making contact one with the other through the registered notches.
7. In a construction of the character described, a pair of thermo electric members, one of said members having therein a notch in which the other member is engaged, tubular enclosures for said elements one of which is notched to receive therein the enclosure of the other element, the other of which is notched to accommodate the element enclosed in the first mentioned enclosure. 30
8. In a construction of the character described, a plurality of nonconductive members having thermo electric cores, said members having interlocking notches wherein the cores are exposed for contact one with another.

In testimony whereof, I have hereunto set my hand this 5th day of May A. D. 1917.

FRANK W. ANDREWS.
